PROCESS AND APPARATUS FOR REFINING CLAY, &c.

1,222,979.

Specification of Letters Patent. Patented Apr. 17, 1917.

Application filed July 6, 1916. Serial No. 107,750.

To all whom it may concern:

Be it known that I, STANLEY A. W. OKELL, a subject of the King of Great Britain, and resident of East Orange, Essex county, State of New Jersey, have made a certain new and useful Invention Relating to Processes and Apparatus for Refining Clay, &c., of which the following is a specification, taken in connection with the accompanying drawing, which forms part of the same.

This invention relates particularly to refining of clay or generally similar solid material which can be easily suspended in water, by continuous centrifugal separating methods while the material is in suspension in aqueous or other liquid. Clay such as is used for paper making, for instance, may in its raw state be suspended in water by suitable agitation to the extent of about ten per cent. more or less and this liquid or raw clay solution as it will be termed for brevity may, preferably after screening to remove any undesirable large particles, be fed into a centrifugal drum provided with ribs or partitions to promote the quiescence of the rotating body of liquid or clay solution therein. The centrifugal action thus effected is sufficient to separate the usual fine particles of grit and drive them outward through the more or less gelatinous or colloidal clay solution and these particles of grit while still suspended in liquid may pass through discharge slots or openings in the periphery of the drum so as to enter the annular space or chamber between the drum and the casing surrounding it where this separated material is kept in suspension by the intense agitation or swirling of the liquid, so that, if desired, it can be continuously discharged while in this condition, the refined clay material while suspended in liquid being, if desired, continuously discharged from the central part of the centrifugal drum.

An illustrative form of apparatus for carrying out this invention is shown in a somewhat diagrammatic way in the accompanying drawing in which—

Figure 1 is a substantially vertical section taken along the line 1—1 of Fig. 2; and

Fig. 2 is a transverse horizontal section taken along the line 2—2 of Fig. 1.

In this illustrative form of apparatus, the casing 3 may be supported in any suitable

way and may have its ends closed tightly as by the plates 7 and 15 bolted or otherwise secured thereto as by bolts, such as 25. The centrifugal drum which may, if desired, be mounted vertically within this casing may comprise the end 5 screwed, soldered or otherwise secured to the periphery of the drum and formed with a boss or enlargement 6 in which may be secured the drum axle 39 passing through a suitable stuffing box 8 formed on or secured to the bottom plate 7. A thrust bearing of any desired form may be arranged in connection with this axle and may, for instance, comprise the conical thrust bearing members 9 engaging a raceway in the bearing plate 10 secured to lugs on the bottom plate 7, if desired. To rotate the drum any suitable driving mechanism may be employed, and for instance, an electric motor 11 may be directly connected with the drum axle and may rotate the drum at the proper speed to secure the desired centrifugal action. The drum may be provided with a similar upper end member 16 to which may be secured the tubular shaft 12 extending through the packing box 14 and into a discharge chamber or casing 17 mounted, if desired, on the transverse member 23 of the head frame 24. This discharge chamber may be provided with a discharge pipe 22 communicating with the space 18 within the chamber and suitable packing 21 may be arranged within the neck 20 secured to the bottom of this chamber which may fit somewhat loosely around the tubular shaft 12. In order to deflect the liquid rising in this tubular shaft a flaring collar or deflector 19 may be secured to the shaft in such position as to project down over the top of the neck 20 and direct the liquid into the space 18 in the discharge chamber without undesirable leakage.

The clay or the like suspended in water or other suitable liquid to the extent of some ten per cent. more or less may be fed into the drum, as for instance through the feed pipe 13 which is preferably centrally arranged along the axis of the drum and adjustably held in position as by the set screw 28 in the block 27 secured to the top plate of the head frame which may be removably held in position by the bolts 26. The upper end of this feed pipe may be provided with a supply funnel 29 with which the supply pipe 110

30 may coöperate and in this way the raw
clay solution and grit may be continuously
fed into the centrifugal drum adjacent its
axis and preferably near the lower end of
5 the drum toward which the discharge end 38
of the feed pipe approaches. Under oper-
ating conditions the drum is filled with this
clay solution which is maintained in rapid
10 rotation with a minimum of eddies or dis-
turbance by reason of the baffle plates or ribs
40 which may be arranged at any suitable
intervals within the drum preferably in a
more or less radial position and the centrifu-
gal force thus generated is sufficient to cause
15 the heavier fine particles of grit or simi-
lar material to force themselves outward
through the somewhat colloidal clay solution,
so that these grit particles can be discharged
through suitable discharge slots or open-
20 ings 42 which are preferably located about
in the middle of the circumference of each
of the chambers between these drum ribs, the
slots being preferably discontinuous as indi-
cated in Fig. 1 to avoid undesirably weak-
25 ening the drum. If desired suitable inclined
partitions 41 may be arranged within the
drum to guide the discharged material to-
ward the discharge slots, although this is
not in all cases necessary since the heavier
30 material tends to build up in the corners of
each drum chamber in somewhat inclined po-
sition generally similar in contour to these
partitions under operating conditions. This
heavier discharged grit or material thus en-
35 ters the annular space around the rotating
centrifugal drum and is kept uniformly in
suspension in the water therein because of
the strong swirling or agitation caused by
the rotation of the drum in this narrow an-
40 nular space in the inclosing casing. By suit-
ably regulating the amount discharged from
this space in proportion to the liquid dis-
charged from the central part of the cen-
trifugal drum the grit may be discharged
45 from the outer casing while suspended in
liquid, as for instance, through the ejector
pipe 31 which may be formed with suitable
means to regulate this discharge, as for in-
stance the adjustable outlet portion 35 ad-
50 justably connected as by the flexible joint 34
with the ejector pipe so that the position of
the end 37 of this outlet portion may be
regulated, between pins 36, for example. In
this way the centrifugal force due to the ro-
55 tation of the drum causes sufficient static
head within the outer casing so as to continu-
ously discharge the liquid and suspended
grit through this ejector pipe which prefer-
ably has such small diameter that the speed
60 of the liquid through this pipe is sufficient
to keep the fine grit particles in suspension.
The adjustable end of the ejector pipe is ex-
tended up far enough so as to regulate the
amount of this discharge by partially coun-
65 teracting the static pressure due to this cen-

trifugal action of the drum. If desired, a
valved discharge may be arranged in con-
nection with this ejector pipe 31 either in ad-
dition to or instead of the adjustable outlet
portion thereof and such an arrangement is
70 shown in the drawing as comprising the
valve 32 and connected discharge pipe 33
connected to the ejector pipe adjacent its
lower portion so that, for example, the pipe
can be readily drained in this way when the
75 apparatus stops, or if the upwardly extend-
ing outlet portion is not used as a discharge
the extent to which this valve is opened may
regulate the amount of liquid discharged
from this casing. The relatively lighter clay
80 solution which remains near the center of the
centrifugal drum under operating conditions
may be continuously discharged therefrom
through the annular space between the tubu-
lar shaft 12 and the feed pipe 13 which pref-
85 erably discharges this refined clay solution
from the end of the centrifugal drum which
is opposite to or remote from the place where
the raw clay solution is fed to the drum.
This refined clay solution may then flow out
90 of the discharge chamber 17 through the dis-
charge pipe 22 into any suitable container or
apparatus where the clay may be freed from
the water and utilized in any desired way.
It is of course understood that either the clay
95 solution or the heavier gritty material or
both may be passed through a second cen-
trifugal separator of this character to re-
move from each of the products any small
proportion of the other that it may contain,
100 although this is not in all cases necessary
since a single centrifugal separation of this
kind removes practically all the objection-
able grit from the clay and in a much cleaner
and more thorough manner than can be se-
cured by any gravitational or other usual
methods.

This invention has been described in con-
nection with a number of illustrative forms,
proportions, parts, and arrangements of ap-
paratus and methods of use, steps and con-
ditions, to the details of which disclosure the
invention is not of course to be limited, since
what is claimed as new and what is desired
to be secured by Letters Patent is set forth
110 in the appended claims:

1. The continuous process of centrifugally
refining clay, which consists in suspending
raw clay in water to the extent of about ten
per cent. thereof, in subjecting a body of
120 such raw clay solution to centrifugal action
and in preventing undesirable eddies therein,
in continuously removing separated heavier
particles of grit, etc., from said body of raw
clay solution and agitating them to keep
125 them suspended in water during their dis-
charge in suspension, in continuously remov-
ing the solution of the remaining purified
clay while in suspension in water and in con-
tinuously feeding raw clay solution to the
130

body thereof undergoing centrifugal action at a point remote from the point of removal of the purified clay therefrom.

2. The continuous process of centrifugally refining clay, which consists in suspending raw clay in water, in subjecting a body of such raw clay solution to centrifugal action, in continuously removing separated heavier particles of grit, etc., from said body of raw clay solution and agitating them to keep them suspended in water during the solution of the remaining purified clay while in suspension in water and in continuously feeding raw clay solution to the body thereof undergoing centrifugal action at a point remote from the point of removal of the purified clay therefrom.
3. The continuous process of centrifugally refining clay, which consists in suspending raw clay in water, in subjecting a body of such raw clay solution to centrifugal action, in continuously removing separated heavier particles of grit, etc., from said body of raw clay solution, in continuously removing the solution of the remaining purified clay while in suspension in water and in continuously feeding raw clay solution to the body thereof undergoing centrifugal action.

4. The continuous process of centrifugally refining clay, etc., which consists in suspending the raw material in water to the extent of about ten per cent. thereof, in subjecting a body of such raw material solution to centrifugal action and in preventing undesirable eddies therein, in continuously removing separated heavier particles of waste material including grit, etc., from said body of raw material solution and agitating such waste material to keep it suspended in water during its discharge in suspension, in continuously removing the solution of the remaining purified clay while in suspension and in continuously feeding such solution of raw material to the body thereof undergoing centrifugal action.

5. The continuous process of centrifugally refining clay, etc., which consists in suspending the raw material in water, in subjecting a body of such raw material solution to centrifugal action, in continuously removing separated heavier particles of waste material including grit, etc., from said body of raw material solution and agitating such waste material to keep it suspended in water during its discharge in suspension, in continuously removing the solution of the remaining purified clay while in suspension and in continuously feeding such solution of raw material to the body thereof undergoing centrifugal action.

6. The continuous process of centrifugally refining clay, etc., which consists in suspending the material in liquid, in subjecting a body of such raw material solution to centrifugal action, in continuously removing

separated heavier particles of waste material including grit, etc., from said body of raw material solution and agitating such waste material to keep it suspended in liquid during its discharge in suspension, in continuously removing the solution of the remaining purified clay while in suspension and in continuously feeding such solution of raw material to the body thereof undergoing centrifugal action.

7. The process of centrifugally refining clay, which consists in suspending the raw clay in water to the extent of about ten per cent. thereof, in subjecting a body of such raw clay solution to centrifugal action and in preventing undesirable eddies therein, in removing separated heavier particles of grit, etc., from said body of raw clay solution and agitating them to keep them suspended in water during their discharge in suspension, and in simultaneously removing the solution of the remaining purified clay while in suspension in water.

8. The process of centrifugally refining clay, which consists in suspending the raw clay in water, in subjecting a body of such raw clay solution to centrifugal action and in preventing undesirable eddies therein, in removing separated heavier particles of grit, etc., from said body of raw clay solution and agitating them to keep them suspended in water during their discharge in suspension, and in removing the solution of the remaining purified clay while in suspension in water.

9. The process of centrifugally refining clay, which consists in suspending the raw clay in water, in subjecting a body of such raw clay solution to centrifugal action, in removing separated heavier particles of grit, etc., from said body of raw clay solution, and in removing the solution of the remaining purified clay while in suspension in water.

10. The apparatus for refining clay, etc., comprising a vertical cylindrical casing, a centrifugal drum within said casing and closely approaching the sides thereof, means to rotate said drum at substantially uniform speed, a tubular shaft communicating with the inside of said drum and extending upward through said casing, a discharge chamber and pipe with which said tubular shaft communicates, a feed pipe adjustably mounted to extend substantially axially within said tubular shaft and drum to discharge liquid material adjacent the bottom of the drum, an ejector pipe communicating with said casing adjacent the bottom thereof and provided with adjustable means to regulate the amount of material discharged from said ejector pipe, said drum being formed with a series of radial ribs to form chambers within said drum and with discharge slots in the periphery of said drum communicating with

each of said chambers and inclined partitions extending between the periphery of the drum adjacent each of said discharge slots and the adjacent ribs to deflect outwardly 5 moving material into said slots.

11. The apparatus for refining clay, etc., comprising a vertical cylindrical casing, a centrifugal drum within said casing and closely approaching the sides thereof, means 10 to rotate said drum at substantially uniform speed, a tubular shaft communicating with the inside of said drum and extending upward through said casing, a discharge chamber and pipe with which said tubular shaft 15 communicates, a feed pipe mounted to extend substantially axially within said tubular shaft and drum to discharge liquid material adjacent the bottom of the drum, an ejector pipe communicating with said casing 20 adjacent the bottom thereof and provided with adjustable means to regulate the amount of material discharged from said ejector pipe, said drum being formed with a series of radial ribs to form chambers within said 25 drum and with discharge slots in the periphery of said drum communicating with each of said chambers.

12. The apparatus for refining clay, etc., comprising a vertical cylindrical casing, a 30 centrifugal drum within said casing and closely approaching the sides thereof, means to rotate said drum at substantially uniform speed, a tubular shaft communicating with the inside of said drum and extending

upward through said casing, a discharge 3 chamber and pipe with which said tubular shaft communicates, a feed pipe mounted to extend substantially axially within said tubular shaft and drum to discharge liquid material adjacent the bottom of the drum, 40 an ejector pipe communicating with said casing adjacent the bottom thereof, said drum being formed with a series of chambers within said drum and with discharge slots in the periphery of said drum communicat- 45 ing with each of said chambers.

13. The apparatus for refining clay, etc., comprising a casing, a centrifugal drum within said casing to agitate the liquid in said casing around said drum, means to 50 rotate said drum at substantially uniform speed, a discharge passage communicating with the inside of said drum and extending through said casing, a feed pipe mounted to discharge liquid material adjacent the axis 55 of the drum and an ejector pipe communicating with said casing adjacent the bottom thereof and provided with adjustable means to regulate the amount of material discharged from said ejector pipe, said drum being formed with a series of chambers and with discharge slots in the periphery of said drum communicating with each of said chambers.
